UNITED STATES PATENT OFFICE.

FRANK H. SLEEPER, OF WORCESTER, MASSACHUSETTS, ASSIGNOR TO SLEEPER & HARTLEY, INC., OF WORCESTER, MASSACHUSETTS, A CORPORATION OF MASSACHUSETTS.

SUPPLY-REEL FOR WIRE-COILS.

1,287,776.

Specification of Letters Patent. Patented Dec. 17, 1918.

Application filed November 28, 1917. Serial No. 204,456.

To all whom it may concern:

Be it known that I, FRANK H. SLEEPER, a citizen of the Dominion of Canada, residing at Worcester, in the county of Worcester 5 and Commonwealth of Massachusetts, United States of America, have invented a new and useful Improvement in Supply-Reels for Wire-Coils, of which the following, together with the accompanying drawings, is a specification.

The present invention relates to improvements in reels of the type employed for supporting coils of wire and the like, and from which the wire is drawn, either continuously 15 or intermittently, for use in various types of wire working machinery.

The invention resides in a novel construction of reel which is adapted to prevent spreading or springing out of the coil of wire held thereon by the natural resiliency 20 of the material, and which is adjustable to various sizes of coils held thereon as regards the inner peripheries of said coils. The invention is fully set forth in the following 25 description, reference being had in this connection to the accompanying drawings, in which—

Figure 1 is a view in elevation of my improved reel.

Fig. 2 is a plan view of the reel shown in Fig. 1.

Fig. 3 is an enlarged view of the reel, partly in elevation and partly in vertical section.

Fig. 4 is a sectional view on the line 4—4, Fig. 3.

Similar reference characters refer to similar parts in the different figures.

As shown in Fig. 1, the reel is carried on 40 a post or shaft 1, which rises from a suitable base 2. An elongated sleeve 3 surrounds shaft 1 and is movable rotatively and longitudinally with respect thereto. At the upper and lower ends of said sleeve are secured plates 4 and 5, respectively, which plates constitute the heads or ends of the core portion 45 of the reel, i. e., that portion which is received within the inner periphery of the annular coil of wire.

In the present construction, said core portion 50 comprises a series of strips 6, 6, here shown as six in number, the upper and lower end of each strip 6 being bent inwardly and horizontally, as shown at 7 and 8 respectively, and attached by rivets 9 or the like, to the plates 4 and 5 respectively. In this

way a skeleton core portion is formed for the reel which extends throughout the entire length of the sleeve 3, and which is rotatable bodily as a unit about the shaft 1. As herein 60 shown said core portion is frusto-conical in outline, due to the lower horizontal sections 8 of the bars or strips 6 being longer than the upper horizontal sections 7. In this way a core portion of varying cross section is 65 provided, the lower part thereof being suitable for coils of wire of large internal diameter, and the upper part thereof being suitable for coils of wire of small internal diameter.

For coöperation with the frusto-conical core portion above described, my improved reel provides an adjustable coil supporting and confining member which as herein 70 shown comprises a casting or plate 10 adjustably secured to the sleeve 3 by means of a set screw 11, or the like. Radiating from the casting 10 is a series of bars 12, 12, here shown as six in number, with their outer ends upturned to form a circular series of vertical sections 13, joined at their tops by rivets 14 or the like to a ring 15. The floor or bottom of this coil supporting 75 and confining portion of the reel is constituted by the horizontal portions of the bars 12, and its outer wall is constituted by the vertical sections 13. The coil supporting 80 and confining portion of the reel rotates in unison with the core portion, due to the attachment of plate or casting 10 to the sleeve 90 3, and hence the strips 6 constitute the inner wall of the core receiving space, as indicated in Fig. 3. It will thus be seen that the reel is adjustable to coils of wire of varying 95 diameters, owing to the frusto-conical form of the core portion, and to the above described adjustable connection of the coil supporting and confining portion to said core portion. For a coil of wire of small internal diameter the coil supporting and 100 confining portion is secured near the top of the sleeve 3 by the set screw 11, while for a coil of larger internal diameter it is moved downward. For preventing convolutions of the coil from springing up and out of the annular coil receiving space thus provided, the 105 projecting fingers 16 are preferably employed, these fingers being adjustably secured to the inclined portions of the strips 6 by means of thumb screws 17, or the like.

The reel as above described is supported 110 on the shaft 1 by means of a collar 18,

against the upper face of which bears the sleeve 3 and the hub of plate 5, as shown in Fig. 3. This collar 18 is held fast to the shaft 1 by means of a set screw 19 or the like, which may be loosened to effect a vertical adjustment of said collar and thereby vary the height of the reel to suit different conditions of operation. Said collar 18 provides a groove 19' in its outer surface 5 for the reception of a pair of segmental members 20, 20, having projecting arms 21, 21, which receive between them a depending pin 22, secured to the plate 5 of the reel structure. The members 20, 20, are held 10 in contact with the groove in collar 18 by means of a bolt 23 passing loosely through the arms 21 and carrying a spring 24 between one of said arms and a nut 25 on the end of said bolt. The spring 24 draws the members 20, 20, together, yieldingly, so as to hold them in the groove of collar 18, and thereby said members constitute a brake for the reel, to slacken its rotation when the draft on the wire being drawn therefrom 15 ceases. Such a brake is delicately adjustable by means of the nut 25, which may be moved on the bolt 23 to increase or decrease the friction or drag of members 20 on the collar 18 as conditions require.

20 I claim,

1. In a device of the character described, a frusto-conical core section and a surrounding coil supporting section axially adjustable relative on said core section.

2. In a device of the character described, a frusto-conical core section, a surrounding coil supporting section extending beyond the core section, and means for adjustably supporting said coil supporting section on said 25 core section, whereby it is capable of axial adjustment on the core section.

3. In a device of the character described, a rotatable core section frusto-conical in

cross section, a coil supporting section extending beyond said core section, means for 45 supporting said coil section on the core section capable of axial adjustment thereon, and means for applying a brake to said core section.

4. In a device of the character described, 50 a core section frusto-conical in cross section, a coil supporting section extending beyond said core section and axially adjustable thereon, and fingers adjustably supported by the core section and extending 55 over said coil section.

5. In a device of the character described, a skeleton core section frusto-conical in cross section and comprising a series of spaced longitudinal bars, a coil supporting section 60 extending beyond and adjustably supported by the core section, and fingers adjustably held on said longitudinal bars and overhanging said coil supporting section.

6. In a device of the character described, 65 a vertical shaft, a support therefor, a core section frusto-conical in cross section and comprising a sleeve vertically adjustable on said shaft, a coil supporting section adjustably held on said sleeve and extending beyond the core section, and means for adjusting said sleeve on said shaft.

7. A supply reel for coils, comprising a rotatable skeleton core portion, frusto-conical in form, and a surrounding attached 75 coil supporting portion, circular in form, and means for adjusting said last named portion axially with respect to said first named portion, whereby to vary the internal diameter of the annular coil receiving space.

Dated this 23rd day of November, 1917. 80

FRANK H. SLEEPER.
